AUTOMATIC REGISTERING DEVICE FOR
IMPULSE SERIESAnton Christian Jacobaeus, Stockholm, Sweden,
assignor to Telefonaktiebolaget L M Ericsson,
Stockholm, Sweden, a company of SwedenApplication November 19, 1945, Serial No. 629,605
In Sweden January 9, 1945

4 Claims. (Cl. 179—25)

1

By transmission of figures in a telephone number from a telephone exchange to another or from a telephone instrument to an automatic telephone exchange, impulse series are usually used, in which the number of impulses indicates the value of the figure. Sometimes, however, impulses of different kinds are sent in different combinations, shorter impulse-series thus being obtained and the transmission being carried through more quickly. Such combinations of impulses are received by special impulse-receiving devices and registered in automatic registers, which afterwards set the selectors.

The present invention refers to a simple and reliable method of receiving and registering signals among which are electric impulses of more than one kind. For that purpose, a cross-bar switch is used, in a way known per se, as a registering member and the invention consists of the selecting magnets of said cross-bar switch being actuated from different impulse-receiving devices by closing circuits passing contact devices on the cross-bar switch itself, said contact devices being different for each impulse-receiving device.

The invention will be more closely described with reference to the accompanying drawings: In Fig. 1 there is shown a registering device, in which R1, R2—R8 are relays, BM0, BM1—BMn operating magnets in a cross-bar switch, STM1, STM2—STM10 selecting magnets in the same cross-bar switch and K1—K2 contact rows on the operating bar, which is actuated by the magnet BM0. In the example of practice of the invention shown in Figure 1, two kinds of electric impulses such, for instance, as alternating current of different frequencies are conducted by wires a and b. One kind of impulses operates a first impulse receiving relay R1 over wire b and the other operates a second impulse receiving relay R2 over wire a.

We suppose now that the registering device is busied by the wire c being connected to the positive pole of the exchange battery and an impulse coming in over wire b, impulse receiving relay R1 then attracting its armature. Contacts 11 and 12 are actuated. A first operating relay R3 attracts its armature on contact 11 closing, and is held over contacts 31 and 51. Contacts 31—35 are operated. A slow release R6 attracts its armature on contact 33 closing. Contacts 61—63 are actuated. At the same time selecting magnet STM1 attracts its armature in the following circuit: + (i. e. the positive pole of the exchange battery), contacts 34 and 79, winding 55 relay R5 attracting its armature, contact 53

2

on magnet STM1 to negative, (i. e. the negative pole of the exchange battery). Selecting magnet STM1 attracts its armature.

At the end of the impulse, impulse receiving relay R1 releases its armature and the following circuit is completed: +, contacts 12 and 32, winding on first holding relay R5 to negative. Relay R5 attracts its armature and contacts 51—55 are actuated. The holding circuit for operating relay R3 is broken by contact 51, and relay R3 releases its armature. The selecting magnet STM1 is held in the following circuit: +, contact 55, a winding on each one of the magnets STM1—STM10 to negative. In that circuit none of the selecting magnets STM1—STM10 is able to attract its armature, the current intensity being arranged so that only an already actuated magnet can hold its armature. At the same time the following circuit is completed: +, contacts 52 and 74, winding on operating magnet BM0 to negative. Magnet BM0 attracts its armature, contacts 101 and 102 and the contacts corresponding to selecting magnet STM1 in the contact rows K1 and K2 are closed. Operating magnet BM0 is self-bound with current over contacts 62, 101 and 74.

When operating relay R3 releases its armature first holding relay R5 also releases its armature.

The following circuit is completed: +, contacts 63, 54, 102, winding on relay R7 to negative. Relay R7 attracts its armature and the contacts 71—79 are operated. Relay R7 binds itself over contacts 63 and 76. Relay R6 has a time delay factor and therefore remains operated during the pause between two impulses in an impulse-series.

The operating magnet BM0 is held through a circuit over the contacts 53 and 75. The selecting magnet STM1 is held in a circuit over the contacts 35, 45 and 78.

Hereafter we suppose that another impulse comes in over wire b so, that the impulse receiving relay R1 and operating relay R3 again attract their armatures, the current for selecting magnet STM1 then being broken over contact 35. After the end of the impulse, the first holding relay R5 attracts its armature. The following circuit is completed: +, contact 34, the contact corresponding to selecting magnet STM1 in the contact column K1, winding on selecting magnet STM2 to negative. The selecting magnet STM2 attracts its armature and is being held as described above with regard to STM1 till the beginning of the next impulse. On the first holding relay R5 attracting its armature, contact 53

breaks the current for operating magnet BM_9 , which then releases its armature. On the first holding relay R_5 again releasing its armature according to the above description, the circuit is completed anew over contact 53 for operating magnet BM_0 , which again attracts its armature. This time, however, the contacts corresponding to selecting magnet STM_2 in the contact columns K_1 and K_2 are closed.

If further impulses keep on coming in over wire b without any interruption long enough to allow the slow release relay R_6 to release its armature, one contact set after the other will, according to the description above, be closed each in its turn in the contact columns K_1 and K_2 . Suppose now, that five impulses consecutively come in over wire b , the contacts corresponding to selecting magnet STM_5 in the contact columns K_1 and K_2 will then be closed, and only selecting magnet STM_5 will hold its armature attracted through the mentioned current from $+$, over contacts 35 , 45 and 78 and through windings on all the selecting magnets STM_1 – STM_{10} to negative. If the impulse-series is thus completed, the slow release relay R_6 will release its armature after a short time, following circuit being closed: $+$, contacts 61 , 73 , 84 , and 113 , winding on operating magnet BM_1 to negative. The circuit for the second holding relay R_7 is broken by contact 63 , but this relay is somewhat slow at release, owing to what the operating magnet BM_1 has time to attract its armature during the release-time of the second holding relay R_7 . Operating magnet BM_1 is self-bound over contact 114 and wire c to positive, the signal corresponding to the first impulse series thus being registered. On the second holding relay R_7 releasing its armature the following circuit is completed: $+$ wire c , contacts 71 , 121 and 111 , winding on magnet operating relay R_8 to negative. Magnet operating R_8 attracts its armature. The contacts 82 – 84 are actuated.

On the next impulse-series the above process is repeated, if again only impulses of the kind, which comes in over wire b , are included in the impulse-series. After the end of the impulse-series however, the process becomes another, the magnet operating relay R_8 having attracted its armature and holding it, even on the second holding relay R_7 being actuated, owing to the following circuit: $+$, wire c , contacts 72 and 82 , winding on the magnet operating relay R_8 to negative. On the slow release relay R_6 releasing its armature after the end of the impulse-series, the following circuit is completed: $+$, contacts 61 , 73 , 83 , 112 and 123 , winding on operating magnet BM_2 to negative. Operating magnet BM_2 attracts its armature and the signal corresponding to the second impulse series is registered by closing of contacts, which are not shown on the figure. The operating magnet BM_2 binds itself over contact 124 . After the second holding relay R_7 has released its armature, the magnet operating relay R_8 also releases its armature, since now the holding current over contacts 71 , 121 and 111 is broken in contact 121 .

In a similar way, signal after signal is registered on the operating magnets BM_1 – BM_n . The magnet operating R_8 attracts its armature after every second impulse-series.

If any of the impulse series is the kind which comes in over wire a , the relay second impulse receiving R_2 and the second operating relay R_4 will be actuated instead of the first impulse receiving relay R_1 and the first operating relay R_3 .

while the other relays R_5 – R_8 and the operating magnet BM_0 will work according to the description above. On the first impulse in such an impulse series the contacts 21 – 22 and 41 – 45 are thus operated. The following circuit is completed: $+$, contacts 35 , 44 and 71 , winding on selecting magnet STM_3 to negative. Selecting magnet STM_3 attracts its armature and is held first with current over contact 55 , then after the end of the first impulse with current over contacts 35 , 45 and 78 . After the end of the impulse, the first holding relay R_5 attracts its armature, this time with current over contacts 22 and 42 . The holding circuit for the second operating relay R_4 over contacts 41 and 51 is broken by contact 51 . The second operating relay R_4 and thereafter the first holding relay R_5 release their armatures, after which the operating magnet BM_6 attracts according to the description above. If thereafter the next succeeding impulses are of the kind which come in over wire b , the selecting magnets STM_4 – STM_{10} are actuated one after the other in accordance with the preceding description. Consequently these impulses over the wire b are the equivalent of one impulse over the wire a and a shorter impulse series is thus obtained. If on the other hand a second impulse also comes in over the wire a , additional impulses of the kind which come in over the wire b can be replaced by means of the contact column K_2 with only one impulse of the kind that comes in over the wire a . As shown in Figure 1 the second impulse receiving relay R_2 and the second operating relay R_4 attract their armatures when the second impulse comes in over the wire a and the following circuit is completed: $+$, contacts 35 and 44 , the contact corresponding to selecting magnet STM_3 in the contact column K_2 , winding on selecting magnet STM_9 to negative. Selecting magnet STM_9 attracts its armature and holds it until the beginning of the next impulse or until the second holding relay R_7 has released its armature. After the end of the impulse the second operating relay R_4 and the first holding relay R_5 release their armatures. Operating magnet BM_9 , which released its armature on the first holding relay R_5 being operated, again attracts its armature. The contacts corresponding to selecting magnet STM_9 in the contact rows K_1 and K_2 then close. If the impulse series ends herewith, and for instance corresponds to the third figure or the third signal to be registered, the following circuit is completed on the slow release relay R_6 releasing its armature: $+$, contacts 61 , 73 , 84 , 122 and 133 , winding on operating magnet BM_3 to negative. Operating magnet BM_3 attracts its armature and is held over contact 134 . The contacts 131 – 134 and the contacts (not shown in Figure 1) on the operating bar corresponding to the magnet BM_3 are closed, said last mentioned contacts corresponding to selecting magnet STM_9 .

It appears from the description above, that signals containing impulses of two kinds can be registered in the cross bar switch shown in the Figure 65 1. The two contact columns K_1 and K_2 are connected in Figure 1 so that 10 different signals corresponding to the Figures 1–9, 0 can be received. In Fig. 2 the existing combinations are shown, two different kinds of signals being marked by R_1 , R_2 , respectively, in order to show which one of the impulse receiving relays R_1 , R_2 , respectively, receives the signal.

It can be understood from the description above, that the invention is not limited to a signal comprised by only two kinds of impulses. If

three kinds of impulses are desired, there need only be added another relay corresponding to the impulse receiving relays R1 and R2 and an auxiliary relay corresponding to the operating relays R3 and R4. Further another contact row on the operating bar corresponding to the operating magnet BM1 and a new connection, easy to arrange by one skilled in the art, are needed. It is not altogether necessary to use a so-called impulse operating bar, that is, the operating bar corresponding to the operating magnet BM3 in the cross-bar switch, but the contacts contained in the contact columns K1 and K2 can be actuated directly by the selecting magnets STM1-STM10, special auxiliary relays, however, then being needed for the operation of the selecting magnets. Such relays have been known for a long time. The different kinds of impulses must however close circuits, which include special contacts for each kind of impulses on the selecting magnets, as well as they, according to Fig. 1, include contacts in separated contact columns, K1 and K2 in the cross bar switch.

I claim:

1. In a telephone system wherein a register including a cross bar switch is utilized for recording impulses on the line, said cross bar switch having contacts arranged in rows and pairs of columns, at least one operating bar for controlling the pairs of columns of contacts, a combination magnet and relay for actuating said operating bar, selecting magnets corresponding to the rows of contacts and having operating and holding windings thereon, the holding windings of the various selecting magnets being interconnected, and one contact in each row and one of said columns being connected to the operating winding of the selecting magnet corresponding to the next row, said register having a plurality of relays in serial arrangement including an impulse receiving relay, an operating relay, a first holding relay, a slow release relay, and a second holding relay, means responsive to energization of the impulse receiving relay for energizing the operating relay, means responsive to energization of the operating relay and including the first holding relay for establishing a holding circuit for the operating relay, means also responsive to energization of the operating relay for establishing an operating circuit for the slow release relay, means also responsive to energization of the operating relay for establishing a circuit through the second holding relay for the operating winding of the selecting magnet corresponding to the first row of contacts in the cross bar switch to cause the magnet to attract its armature, means responsive to release of the impulse receiving relay for establishing an operating circuit through the operating relay for energizing the first holding relay to break the holding circuit for the operating relay, means responsive to energization of the first holding relay for establishing a first holding circuit for the selecting magnets corresponding, respectively, to two successive rows of contacts in the cross bar switch, means responsive to successive energizations of the first holding relay for establishing a circuit through the second holding relay for the magnet for actuating the operating bar of the cross bar switch whereby successive operations of said bar close the contacts in said column corresponding, respectively, to the first and second selecting magnets, means responsive to a second energization of the operating relay for establishing a circuit including the closed contacts in the said column and first row of contacts of the cross bar switch for the operating winding of the selecting magnet corresponding to the second row of contacts in the cross bar switch, means responsive to energization of the relay associated with the magnet for actuating the operating bar for establishing a first holding circuit for said relay through the slow release relay, means responsive to energization of the relay associated with the magnet for actuating the operating bar for establishing an oper-

operating circuit through the first holding and slow release relays for the second holding relay, means responsive to energization of the second holding relay for establishing a holding circuit through the slow release relay for the second holding relay, means responsive to release of the first holding relay for establishing a second holding circuit through the second holding relay for the magnet for actuating the operating bar, and means responsive to release of the operating relay for establishing a second holding circuit through the second holding relay for the selecting magnet.

2. In a telephone system wherein a register including a cross bar switch is utilized for recording impulses on the line, said cross bar switch having contacts arranged in rows and pairs of columns, at least one operating bar for controlling the pairs of columns of contacts, a combination magnet and relay for actuating said operating bar, selecting magnets corresponding to the rows of contacts and having operating and holding windings thereon, the holding windings of the various selecting magnets being interconnected, and one contact in each row and one of said columns being connected to the operating winding of the selecting magnet corresponding to the next row, said register having a plurality of relays in serial arrangement including an impulse receiving relay, an operating relay, a first holding relay, a slow release relay, and a second holding relay, means responsive to energization of the impulse receiving relay for energizing the operating relay, means responsive to energization of the operating relay and including the first holding relay for establishing a holding circuit for the operating relay, means also responsive to energization of the operating relay for establishing an operating circuit for the slow release relay, means also responsive to the first energization of the operating relay for establishing a circuit through the second holding relay for the operating winding of the selecting magnet corresponding to the first row of contacts in the cross bar switch to cause the magnet to attract its armature, means responsive to release of the impulse receiving relay for establishing an operating circuit through the operating relay for energizing the first holding relay to break the holding circuit for the operating relay, means responsive to energization of the first holding relay for establishing a first holding circuit for the selecting magnets corresponding, respectively, to two successive rows of contacts in the cross bar switch, means responsive to successive energizations of the first holding relay for establishing a circuit through the second holding relay for the magnet for actuating the operating bar of the cross bar switch whereby successive operations of said bar close the contacts in said column corresponding, respectively, to the first and second selecting magnets, means responsive to a second energization of the operating relay for establishing a circuit including the closed contacts in the said column and first row of contacts of the cross bar switch for the operating winding of the selecting magnet corresponding to the second row of contacts in the cross bar switch, means responsive to energization of the relay associated with the magnet for actuating the operating bar for establishing a first holding circuit for said relay through the slow release relay, means responsive to energization of the relay associated with the magnet for actuating the operating bar for establishing an operating circuit for establishing a first holding circuit for said relay through the slow release relay, means also responsive to energization of the relay associated with the magnet for actuating the operating bar for establishing an oper-

ating circuit through the first holding and slow release relays for the second holding relay, means responsive to energization of the second holding relay for establishing a holding circuit through the slow release relay for the second holding relay, means responsive to release of the first holding relay for establishing a second holding circuit through the second holding relay for the magnet for actuating the operating bar, and means responsive to release of the operating relay for establishing a second holding circuit through the second holding relay for the first and second selecting magnets.

3. In a telephone system wherein a register including a cross bar switch is utilized for recording impulses on the line, said cross bar switch having contacts arranged in rows and pairs of columns, at least one operating bar for controlling the pairs of columns of contacts, a combination magnet and relay for actuating the operating bar, selecting magnets corresponding to the rows of contacts and having operating and holding windings thereon, the holding windings of the various selecting magnets being interconnected, and one contact in each row and one of said columns being connected to the operating winding of the selecting magnet corresponding to the next row, said register having a first impulse receiving relay responsive to impulses of one frequency, a first operating relay, means responsive to energization of the first impulse receiving relay for energizing the first operating relay, a second impulse receiving relay responsive to impulses of another frequency, a second operating relay, means responsive to energization of the second impulse receiving relay for energizing the second operating relay, and a plurality of additional relays including a first holding relay, a slow release relay, and a second holding relay, means responsive to energization of the second operating relay and including the first holding relay for establishing a holding circuit for the second operating relay, means also responsive to energization of the second operating relay for establishing an operating circuit for the slow release relay, means also responsive to energization of the second operating relay for establishing a circuit through the first and second operating and second holding relays and the operating winding of the selecting magnet corresponding to the third row of contacts in the cross bar switch to cause the magnet to attract its armature, means responsive to release of the second impulse receiving relay for establishing an operating circuit through the second operating relay for energizing the first holding relay to break the holding circuit for the second operating relay, means responsive to energization of the first holding relay for establishing a first holding circuit for the selecting magnets corresponding, respectively, to three successive rows of contacts in the cross bar switch, means responsive to successive energizations of the first holding relay for establishing a circuit through the second holding relay for the magnet for actuating the operating bar of the cross bar switch whereby successive operations of said bar close the contacts in said column corresponding, respectively, to the first, second, and third selecting magnets, means responsive to energization of the relay associated with the magnet for actuating the operating bar for establishing a first holding circuit for said magnet through the slow release and second holding relays, means also responsive to energization of the relay associated with the

magnet for actuating the operating bar for establishing an operating circuit through the first holding and slow release relays for the second holding relay, means responsive to energization of the second holding relay for establishing a holding circuit through the slow release relay for the second holding relay, means responsive to release of the first holding relay for establishing a second holding circuit through the slow release and second holding relays for the magnet for actuating the operating bar, and means responsive to release of the second operating relay for establishing a second holding circuit through the first and second operating and the second holding relays for the said selecting magnets.

4. In a telephone system wherein a register including a cross bar switch is utilized for recording impulses on the line, said cross bar switch having contacts arranged in rows and pairs of columns, at least one operating bar for controlling the pairs of columns of contacts, a combination magnet and relay for actuating the operating bar, selecting magnets having operating and holding windings thereon and arranged seriatim in two groups corresponding to the rows of contacts, the holding windings of the selecting magnets of both groups being interconnected, and one contact in each row and one of said columns being connected to the operating winding of the selecting magnet in the first group corresponding to the next row and the other contact in each row and the second column being connected, respectively, to operating windings of the selecting magnets in the second group, said register having a first impulse receiving relay responsive to code impulses of one series, a first operating relay, means responsive to energization of the first impulse receiving relay for energizing the first operating relay, a second impulse receiving relay responsive to code impulses of another series, a second operating relay, means responsive to energization of the second impulse receiving relay for energizing the second operating relay, and a plurality of additional relays including a first holding relay, a slow release relay, and a second holding relay, means responsive to energization of the second operating relay and including the first holding relay for establishing a holding circuit for the second operating relay, means also responsive to energization of the second operating relay for establishing an operating circuit for the slow release relay, means also responsive to the first energization of the second operating relay for establishing a circuit through the first and second operating and second holding relays and the operating winding of the selecting magnet in the first group corresponding to the third row of contacts in the cross bar switch to cause the said magnet to attract its armature, means responsive to release of the second impulse receiving relay for establishing an operating circuit through the second operating relay for energizing the first holding relay to break the holding circuit for the second operating relay, means responsive to energization of the first holding relay for establishing a first holding circuit for the selecting magnets, means responsive to successive energizations of the first holding relay for establishing a circuit through the second holding relay for the magnet for actuating the operating bar of the cross bar switch whereby successive operations of said bar close the contacts in both columns corresponding, respectively, to the first, second, and third selecting magnets, means re-

sponsive to a second energization of the second operating relay for establishing a circuit including the closed contacts in the said second column and third row of contacts in the cross bar switch for the operating winding of a selecting magnet in the lower half of the cross bar switch, means responsive to energization of the relay associated with the magnet for actuating the operating bar for establishing a first holding circuit for said magnet through the slow release and second holding relays, means also responsive to energization of the relay associated with the said magnet for establishing an operating circuit through the first holding and slow release relays for the second holding relay, means responsive to release of the first holding relay for establishing a second holding circuit through the slow release and second holding relays for the magnet for actuating the operating bar, and means re-

5

10

sponsive to release of the second operating relay for establishing a second holding circuit through the first and second operating and the second holding relays for the said selecting magnets.
